UNITED STATES PATENT OFFICE

2,046,931

FEED MECHANISM FOR DUPLICATING MACHINES

Charles L. Winter, Chicago, Ill., assignor to
United Autographic Register Co., Chicago, Ill.,
a corporation of Illinois

Application June 7, 1935, Serial No. 25,496

17 Claims. (Cl. 101—57)

This invention relates to feed mechanisms for duplicating machines, such as "Addressograph" machines or the like, and, more particularly, to a mechanism for advancing continuous-form stationery through said machines in timed relation to the operation of the machines.

The primary object of the invention is to provide a feed mechanism for automatically advancing successive lengths of continuous-form 10 perforated stationery strips in alignment through impression receiving position, and a supply container for said stationery which can be installed readily on the standard machines now commonly in use.

15 The invention is illustrated in a preferred embodiment in the accompanying drawings, in which—

Figure 1 is a broken side elevational view of a machine embodying the invention; Fig. 1^a, a 20 plan view of length of stationery; Fig. 1^b, a plan view of one of the shiftable printing plates; Fig. 2, a broken plan view of the machine; Fig. 3, an enlarged broken plan view of a portion of the machine taken as indicated at line 3—3 of 25 Fig. 1; Fig. 4, a broken sectional view taken as indicated at line 4 of Fig. 3; Fig. 5, a vertical sectional view taken as indicated at line 5 of Fig. 2; Fig. 6, a sectional view taken as indicated at line 6 of Fig. 7 showing a brake device; 30 Fig. 7, a broken plan sectional view taken as indicated at line 7—7 of Fig. 5; Fig. 8, a broken sectional view of the ratchet mechanism taken as indicated at line 8 of Fig. 2; Fig. 9, a broken sectional view taken as indicated at line 9 of Fig. 2; Fig. 10, a broken sectional view of the lock bolt and housing taken as indicated at line 10 of Fig. 9; Fig. 11, a broken vertical sectional view through the ratchet mechanism taken as indicated at line 11—11 of Fig. 8; Fig. 12, a 35 perspective view of the stationery container, frame and basket; Fig. 13, a perspective view of the guide plate for directing the stationery over a portion of the printing machine mechanism; Fig. 14, a broken sectional view showing a portion of the yieldingly supported lower guide roll; and Fig. 15, a detail sectional view taken as indicated at line 15 of Fig. 12.

Referring to the embodiment illustrated, A 40 designates the main frame of an "Addressograph" machine; B, a vertical chute or magazine for holding a series of printing plates B'; C, a presser arm adapted to press stationery firmly into engagement with an underlying printing plate; D, platen rolls adapted to be reciprocated across the top of the stationery while

the latter is in engagement with a printing plate B'; E, a receiving magazine or tray for printing plates after being fed through from printing position; F, mechanism for feeding printing plates intermittently from the magazine B through printing position to the chute E and for intermittently operating the devices C and D; G, a stationery holder; H, feed mechanism, actuated by the mechanism F, for advancing continuous-form stationery from the holder G; and J, a motor for driving the mechanism F.

Heretofore, "Addressograph" machines have been used to impress a different legend on each successive article fed into impression receiving 15 position. No invention is claimed in this machine per se. As is well understood in the art, the machine is equipped with a reciprocating slide mechanism 16 which is operated by a pitman 17 connected at its rear end to a crank 19 on the shaft 18 which is driven through suitable gears and a belt 20 by the motor J. The mechanism includes a reciprocating conveyor 16^a for moving the printing plates B' seriatim from the magazine B beneath the table 21 of 20 the frame A to impression receiving position and thereafter move them into the receiving magazine E.

In accordance with the present invention, a stationery holder G, as shown in Figs. 1 and 12, 30 is mounted on the table of the machine above the mechanisms C and D. The holder comprises a base member 22 which is adapted to rest loosely on the table and a base member 23 having an inwardly projecting plate 24 provided 35 with a projection 25 adapted to engage a keyway 26 in the table of the machine and held in position by means of a single bolt 27. The base members are provided with suitable standards 28 and 29 which are rigidly connected together by 40 means of cross bars 30 and 31. Preferably, as shown in Fig. 15, the members 28 and 29 are provided with angle members 32 having apertures 33 adapted to receive downwardly extending studs 34 provided on the basket-supporting 45 cross bar 35. As best shown in Fig. 12, the stationery container or basket comprises a pair of longitudinally extending members 36 which are rigidly connected together in spaced relation by means of laterally extending members 37 and is 50 adjustably secured to the cross bar 35. This connection is made at laterally extending slots 38 so that the basket may be adjusted with respect to the printing mechanism. The frame is further provided with uprights 39 connected by 55

a cross bar 40 and supporting at their upper end a laterally adjustable guide roll 41 provided on a shaft 42. The ends of the roll 41 are provided with circumferential flanges to guide the stationery from the basket. Obviously, the roller 41 must be in alignment with the basket. The device is further provided with a lower guide roll 43 which is laterally adjustable on a shaft 44 carried by downwardly extending arms 45 which 10 are pivotally mounted at 46 on the uprights 28 and 29. A coil spring 47 urges the arms rearwardly against a stop 48 and its forward movement is limited by an arm 49 engaging a stop 50, as shown by dotted lines in Fig. 14. In operation, the stationery is advanced intermittently, by jerks, and the yielding mounting of the lower guide roll 43 prevents the stationery from being torn during its advance.

The feed mechanism H is demountably secured on the cross bar 51 provided at the front edge of the table 21. The device is removably secured in position by means of a wing bolt 52, as shown in Fig. 5. The device is provided with forwardly and downwardly projecting arms 53 20 in which is journaled a pinwheel shaft 54 provided with suitable bearing members 55 and spacing members 56. The shaft is provided with a pair of hub members 57 to which are secured outwardly extending pin members 58 having flattened end portions adapted to engage perforations 59 provided in the stationery 60. The device is further provided with an inner fixed 30 guide member 61 provided with arcuate slots 62 through which the pins 58 may extend and engage the stationery. In upwardly extending journal members 63 is mounted a guide roller 64 on the shaft 65. A curved upper guide plate 66 is hinged to the shaft 65, as indicated at 67, and is provided with slots 68 for the pins 58. 35 The shaft is further provided with a rearwardly extending guide plate 69 which is hinged to the shaft 65 at 70 and is adapted to rest lightly on the stationery advancing from printing position. Between the guide members 69 and the guide roller 43 of the stationery holder is provided a curved guide plate 71 adapted to extend forwardly over a portion of the printing mechanism and is supported on studs 72 provided on the frame G.

40 The pinwheel shaft 54 is provided with a brake 73 and is secured to one of the arms 53 by means of a screw 74 and is adjustable by means of a screw 75. The purpose of this device is to prevent overrunning of the wheel in its quick jerky movements. As shown in Figs. 1 and 5, between the guide members 61 and 68 is provided a stripper plate 76 secured in position by means of a bolt 77 and adapted to direct the stationery from engagement with the pins 58.

45 As shown in Fig. 7, the right end of the pinwheel shaft 54 is slotted at 78 so that it may extend into a socket member 79 of the drive mechanism which is provided with a driving pin 80. The socket member 79 has a trunnion 81 which is journaled in a plate 82 and is provided with a fixed pinion gear 83 which, as shown in Fig. 8, meshes with a gear 84 provided on a shaft 85 projecting laterally from the plate 82.

50 As shown in Figs. 7, 9 and 10, the socket member 79 is provided with slots 86 adapted to be engaged by a bolt 87 slidably held on the plate 82 by means of a housing 88. A tension spring 89 urges said bolt into engagement with one of the slots 86. The bolt is provided with a stud 90 extending through a slot 91 in the plate 82 and

is equipped with a roller 92 for withdrawing the bolt against the tension of the spring 89.

The gear 84 is provided with a ratchet wheel 93 which is adapted to be engaged by a pawl 94 pivoted to a cam arm 95 at 96. A spring 97 urges the pawl into engagement with the ratchet. The cam arm 95 is journaled on the shaft 85 and is provided with a cam face 98 which is adapted on oscillation to engage the roller 92 and withdraw the bolt from locking position. On the return stroke, it will engage ratchet teeth and impart a turning movement to the pinwheel shaft 54. The cam member is provided with a radial slot 99 to which is adjustably secured a pitman or link 100 by means of a bolt 101, and the rear end of the pitman is connected at 102 to the reciprocating pitman 17 which is driven by the crank 18. The pitman 100 is adjustable longitudinally by means of a simple bolt extension 103. The supporting plate 82 is removably secured to the frame A by means of a supporting arm 104 and as shown in Fig. 7, is provided with a suitable safety guard 105 secured in position by means of screws 106.

The operation of the device will be readily understood from the above and it will be understood that although the motor J is operating continuously, the feed mechanism H, like the printing mechanism C and D, due to the ratchet device, will operate to move the stationery forwardly intermittently. Whenever the treadle 107 is depressed to begin feeding the printing plates into printing position, the ratchet mechanism will begin to advance successive lengths of stationery in timed relation to the movement of the printing plates. The adjustable connections provided at 99 and 103 permit the length of feed to be varied in accordance with the spacing of the perforations 59 in the stationery 60.

If desired, the stationery holder G may be placed in rear of the chute B and suitable guide rolls used to direct the stationery over the top of the chute. However, it is preferred to mount it as shown. It will be understood, also, that the stationery 60 may be interleaved with coextensive strips of carbon provided with suitable perforations, or, if desired, the carbon may be fed transversely over the printing plate between the stationery strips, as is the usual practice in duplicating machines.

The foregoing detailed description has been given for clearness of understanding only, and no unnecessary limitations should be understood therefrom, but the appended claims may be construed as broadly as permissible, in view of the prior art.

What I claim as new, and desire to secure by Letters Patent, is:

1. In combination: a frame having a table and mechanism for feeding printing plates serially into printing position thereon; feed-means for alining and advancing separate continuous-form stationery strips over said table into impression receiving position above the printing plate in printing position; presser mechanism for pressing said stationery against said plate; and driving means for actuating said mechanisms intermittently in timed relation.

2. A device as specified in claim 1, in which the feed-means comprises movably mounted register pins adapted to engage register perforations provided in each form length of stationery.

3. A device as specified in claim 1, in which the feed-means comprises a wheel equipped with register pins adapted to engage register perfora-

- tions provided in each form length of stationery, and a locking device is provided to lock said wheel while the presser mechanism is in engagement with the stationery.
5. A device as specified in claim 1, in which the feed-means comprises a wheel equipped with register pins adapted to engage register perforations provided in each form length of stationery, and ratchet and locking means is provided adapted to rotate said wheel in but one direction and lock said wheel while the presser mechanism is in engagement with the stationery.
5. In combination: a printing machine having a table with an opening therein to which printing plates may be fed seriatim; presser mechanism over said opening adapted to press stationery into printing engagement with a printing plate positioned in said opening; a stationery holder disposed above said presser mechanism from which zig-zag folded continuous-form stationery may be led into impressive receiving position; and feed mechanism adapted to advance said stationery intermittently one form length in timed relation to the movement of said printing plates.
6. A device as specified in claim 5, in which the stationery holder is provided with a pivotally mounted guide roll adapted yieldingly to direct the stationery into printing position.
7. In combination with a printing machine adapted to impress automatically a different legend at each operation upon successive lengths of stationery fed therethrough; a stationery holder comprising a frame detachably mounted on said machine, a basket mounted on said frame to hold a supply of zig-zag folded continuous-form stationery; a guide roll journaled in said frame above said basket, a second guide roll mounted on said frame below said basket, and a guide plate mounted on said frame beneath the second-mentioned guide roll to direct stationery led from said basket into printing position.
8. A device as specified in claim 7, in which a pair of arms are pivotally mounted on the frame, the second-mentioned guide roll is journaled in the lower ends of said arms, and spring means are provided on said arms to urge said roll rearwardly into yielding contact with the stationery.
9. A device as specified in claim 7, in which the guide rolls are provided near each end with circumferential guide flanges and said flanges and the basket are adjustable laterally with respect to the frame.
10. In combination with a printing machine adapted to impress automatically a different legend at each operation upon successive lengths of stationery fed therethrough; feed mechanism for advancing said stationery comprising a rotatable wheel having outwardly extending register pins, a slotted guide plate for stripping the stationery from engagement with said pins, and means for rotating said wheel intermittently in timed relation to the operation of the printing machine.
11. A device as specified in claim 10, in which means for rotating the wheel comprises a ratchet wheel, an oscillatable pawl in engagement with said wheel, and a pitman connected at one end to
- said pawl and connected at the other end to a rotatable crank provided on the printing machine.
12. In combination with a printing machine adapted to impress automatically a different legend at each operation upon successive lengths of stationery fed therethrough; feed mechanism for advancing said stationery comprising a rotatable wheel having outwardly extending register pins and a bolt slot, a movable bolt for engaging said slot and locking said wheel against rotation, a ratchet wheel for driving the pin-wheel, an oscillatable cam arm adapted to move said bolt from engagement with the slot, a pawl on said cam arm for engaging said ratchet wheel, and a pitman connected at one end to said cam arm and at the other end to a rotatable crank provided on the printing machine.
13. In combination: a printing machine having a frame provided with a table; a magazine of printing plates disposed at the rear of said table; a tray beneath said table for receiving said plates; means for shifting the printing plates seriatim from said magazine through a printing position on said table to said tray; a source of supply for a plurality of separate strips of continuous-form stationery; feeding and alining means for advancing said strips in register through printing position on said table; a platen roll and means adapted to reciprocate said roll intermittently over the stationery in printing position to impress a legend thereon; and driving means for actuating the plate-shifting means, the stationery feeding means, and the platen roll reciprocating means in timed relation.
14. A device as specified in claim 13, in which stationery feeding means comprises a register pin movably mounted on said table and adapted to engage register perforations provided in said strips.
15. A device as specified in claim 13, in which the source of supply for the strips comprises a basket mounted on a frame above platen roll, a guide member on said frame above said basket near the back of said table, and a second guide member on said frame beneath the first-mentioned guide member for directing the stationery into printing position.
16. A device as specified in claim 13, in which the source of supply for the strips is near the rear of the table, and the stationery feeding means is mounted on the front of said table and is equipped with a rearwardly extending guide member for holding the stationery in contact with said table.
17. In combination with a printing machine comprising an upright plate-magazine, a bed extending from the base thereof, means for transferring plates in succession from said magazine to printing position on said bed, and a platen roll disposed above and co-acting with the positioned printing-plate: means for supporting continuous-form stationery; means disposed in front of said magazine for guiding said stationery downwardly to and forwardly over said bed; and intermittently actuated stationery-feeding mechanism operating in timed relation with respect to said printing machine.

CHARLES L. WINTER.

DISCLAIMER

2,046,931.—*Charles L. Winter, Chicago, Ill.* FEED MECHANISM FOR DUPLICATING MACHINES. Patent dated July 7, 1936. Disclaimer filed December 14, 1936, by the assignee, *United Autographic Register Co.*
